UNITED STATES PATENT OFFICE.

SYDNEY L. DAVIS, OF PENSACOLA, FLORIDA.

INTERLOCKING CONCRETE CURB-BLOCK.

No. 895,243.

Specification of Letters Patent.

Patented Aug. 4, 1908.

Application filed March 30, 1908. Serial No. 424,209.

To all whom it may concern:

Be it known that I, SYDNEY L. DAVIS, a citizen of the United States, residing at Pensacola, in the county of Escambia and 5 State of Florida, have invented certain new and useful Improvements in Interlocking Concrete Curb-Blocks; and I do declare the following to be a full, clear, and exact description of the invention, such as will enable 10 others skilled in the art to which it appertains to make and use the same.

This invention relates to concrete curb blocks, and has for its object to provide a curb which may be used in connection with 15 cement sidewalks, thus doing away with the necessity and expense of a board curbing in the making of the sidewalk.

Another object is to provide a curb for a sidewalk which will present a finished appearance and which will serve as a gage in laying the cement walk and as a support and protection for the edge thereof.

Another object is to provide in a curb of this kind locking means to hold the same 25 against lateral displacement on its foundation and additional locking means to hold the curb in firm connection with the concrete sidewalk.

With these and other objects in view, my 30 invention consists in certain novel combinations and arrangement of parts as will be hereinafter fully described and claimed.

In the accompanying drawing, Figure 1 is a perspective view of my improved curb 35 block placed upon a concrete foundation and in connection with a concrete sidewalk; and Fig. 2 shows details of a variety of ways of forming locks on the lower face of the curb.

As shown in the drawings, the preferred 40 embodiment of my invention comprises the curb, generally indicated by the numeral 1, which is shown on a cement foundation, 2, in connection with a sidewalk having a foundation of sand or cinders, 3, on which is 45 placed a layer of concrete, 4, the layer of cement, 5, being placed on top of said concrete, all as clearly shown. The curb block 1 is provided with downwardly projecting locking portions, 6, adapted to be embedded 50 in the concrete foundation of the curb block, and thereby to hold the curb block against lateral displacement.

The upper inner edge of the curb block is 55 cut away as at 7, to form an inwardly projecting portion, 8. The upper part of said inwardly projecting portion is provided with

a groove, 9, extending the length thereof, said groove forming in connection with the upper edge of said inwardly extending projection an upwardly extending locking rib, 60 10, the purpose of which will be presently explained.

The outer upper corner of said curb block is rounded as at 11, to prevent scaling or chipping off and to provide a finished appearance to the block.

The sidewalk to be used in connection with my curb may be as follows: In preparing the sidewalk illustrated in connection with my curb, a layer of sand or cinders or other suitable material, 3, is first placed to substantially the height of the upwardly projecting rib, 10, and firmly rammed in place. The concrete is then spread over the layer, 3, and into the groove, 9, and up as high in the cut- 75 away portion, 7, as is desirable. The vertical space of the cut-away portion 7 may be provided with gage marks, 12, if desired, and the concrete, 4, may be laid even with any one of these gage marks as may be desired. 80 The cement top dressing, 5, is then placed over the concrete, 4, and finished as usual, flush with the top of the curb block.

The curb block 1 may be built of any desired shape, but is preferably of the shape 85 shown in Fig. 1, Fig. 2 showing a variety of shapes which may be used for the lower surface of the curb block.

It is to be understood that I do not limit myself to the exact shape described, but reserve the right to make any changes which lie within the scope and spirit of the invention.

It is thought that the use and advantage 95 of my invention will be understood without further description.

Having thus described my invention, what I claim as new, and desire to secure by Letters-Patent, is:

1. A curb block provided with a cut-away 100 portion at the inner upper edge thereof and extending the length of said curb, said cut-away portion forming an inward projection, a groove extending the length of the upper face of said inward projection and forming an 105 upwardly extending rib.

2. A curb block provided with a cut-away portion at the inner upper edge thereof and extending the length of said curb, said cut-away portion forming an inward projection, 110 a groove extending the length of the upper face of said inward projection and forming an

upwardly extending rib, and downwardly extending longitudinal projections on said curb block.

3. In combination, a curb block having a rounded outer upper edge and longitudinal downward projections, a foundation for said curb block adapted to be seated between said downward projection, a cut-away portion near the upper inner edge of said curb block forming an inward projection with an upwardly projecting rib thereon, a layer of material substantially flush with the upper edge

of said upwardly extending rib, another layer of material extending over and behind said upwardly extending rib, and a top layer on 15 top of said second-named layer.

In testimony whereof I have hereunto set my hand in presence of two subscribing witnesses.

SYDNEY L. DAVIS.
